NOVELTY SCISSORS

Joseph V. Ferriot, Akron, Ohio

Application April 21, 1948, Serial No. 22,449

4 Claims. (Cl. 30—254)

1

This invention relates to scissors.

One object of the invention is to provide scissors, which will not only be amusing to children in use as scissors, but which is adapted to be supported on a surface to serve as an attractive ornament.

Other objects of the invention will be manifest from the following brief description and the accompanying drawing.

Of the accompanying drawing:

Figure 1 is a front elevation of novelty scissors embodying the features of the invention.

Figures 2, 3 and 4 are horizontal cross-sections taken substantially on the lines 2—2, 3—3 and 4—4, respectively, of Figure 1.

Referring to the drawing, there is illustrated scissors comprising members 11 and 12 pivoted together at 13 to have inwardly opposed flat faces 14 and 15, respectively, thereof in substantially superposed relation when the scissors is closed. In the form of the invention shown the members 11 and 12 are shaped, proportioned, and contoured to have a configuration representing a giraffe, although animals, birds or other creatures may be characterized, particularly when the creatures have substantially elongated necks and pedal appendages. A character ostrich, for example, would lend itself well to the present purposes. The members may be of molded hard plastic resin material, to be relatively safe for use by children, or they may be of metal or other material suitable for scissors. When plastic material is used attractive coloring effects may be accomplished in the article-forming or molding process.

The forward member 11 is provided with a body portion 16 in the region of the pivot 13 and an elongated integral extension 17 thereof is provided with a configuration representing the long neck of the giraffe, the same terminating in a head 18. This neck and head constitutes one blade of the scissors, the same having a cutting edge 19 which is shown somewhat curved in accordance with the shape of the back of the neck, but which might be substantially straight, in some instances if desired. An integral handle 20 is provided on member 11 by the extension therefrom of elements 21 and 22 simulating two or more long legs of the giraffe, at least two of these legs being in substantially spaced relation and having a base 23 connected between simulations of hoofs 24 thereof to define a finger or thumb receiving recess 25.

The rear member 12 similarly includes an elongated blade part 26 and an integral handle

2

part 27. The blade 26 has a straight cutting edge 28 for shearing cooperation with edge 19 of blade 17, the opposite edge of the blade being curved to conform substantially to the curvature of the neck of the giraffe, as shown. The handle part 27 may constitute a single leg of the giraffe, terminating at the bottom in a base part 29 which has an upwardly looped, integral extension 30 connecting with an upper portion

10 of leg 27 to provide a finger receiving recess 31. The base parts 23 and 29 are flat on the bottoms and of substantial area, as shown in Figures 1 and 3, whereby the scissors may be supported on a mantel, table or other surface, in closed upright condition (see Figure 1).

In use of the improved scissors for shearing paper, for example, they are held with the fingers received through the handle recesses 25 and 31, and manually operated in conventional manner 20 to move the blades 19 and 26 relatively as illustrated in full and chain-dotted lines in Figure 1. Children are amused by the novel appearance of scissors, and are thereby encouraged to use them as for educational purposes. The scissors, when not in use as such, make an attractive shelf or like ornament, when supported in upright position, as previously described.

Modifications of the invention may be resorted to without departing from the spirit thereof or the scope of the appended claims.

What is claimed is:

1. Toy scissors for children comprising a pair of relatively thin hard plastic outer and inner members pivotally connected to each other, the inwardly opposite sides of said members being flat and engaging in flat face-to-face relation, the portion of said outer member at the pivotal area thereof being of substantially broad lateral area in simulation of the body of an animal, said outer member having an upward extension therefrom in the form of an elongated neck of the animal terminating in a laterally enlarged portion simulating a head thereof, one edge of said neck extension extending in an elongated 35 arc from a point adjacent said pivot to adjacent the outer end of the neck extension and constituting one cutting edge of the toy scissors, said outer member having laterally spaced elongated downward extensions from said body 40 simulating legs of the animal, a base portion between the lower ends of said laterally spaced leg extensions for supporting the scissors in upright position on a surface and defining with the legs an apertured finger-receiving handle, 45 said inner member having an upward extension 50

substantially overlying said neck extension coextensively therewith and constituting the other cutting edge of the scissors, said inner member having an elongated downward extension simulating another leg of the animal and having thereon a looped portion providing an apertured finger-receiving handle in cooperation with said first-named handle, said handles being adapted to have fingers of a hand received through the apertures thereof for pivoting said members relatively of each other to provide shearing action between said cutting edges.

2. Toy scissors for children comprising a pair of relatively thin hard plastic outer and inner members pivotally connected to each other, the inwardly opposite sides of said members being flat and engaging in flat face-to-face relation, the portion of said outer member at the pivotal area thereof being of substantially broad lateral area in simulation of the body of a giraffe, said outer member having an upward extension therefrom in the form of an elongated neck of the giraffe terminating in a laterally enlarged portion simulating a head thereof, one edge of said neck extension extending in an elongated arc from a point adjacent said pivot to adjacent the outer end of the neck extension and constituting one cutting edge of the toy scissors, said outer member having laterally spaced elongated downward extensions from said body simulating legs of the giraffe, a base portion between the lower ends of said laterally spaced leg extensions for supporting the scissors in upright position on a surface and defining with the legs an apertured finger-receiving handle, said inner member having an upward extension substantially overlying said neck extension coextensively therewith and constituting the other cutting edge of the scissors, said inner member having an elongated downward extension simulating another leg of the giraffe and having thereon a looped portion providing an apertured finger-receiving handle in cooperation with said first-named handle, said handles being adapted to have fingers of a hand received through the apertures thereof for pivoting said members relatively of each other to provide shearing action between said cutting edges.

3. Toy scissors for children comprising a pair of relatively thin hard plastic outer and inner members pivotally connected to each other, the inwardly opposite sides of said members being flat and engaging in flat face-to-face relation, the portion of said outer member at the pivotal area thereof being of substantially broad lateral area in simulation of the body of an animal, said outer member having an upward extension therefrom in the form of an elongated neck of the animal terminating in a laterally enlarged portion simulating a head thereof, one edge of said neck extension extending in an elongated arc from a point adjacent said pivot to adjacent the outer end of the neck extension and constituting one cutting edge of the toy scissors, said outer member having laterally spaced elongated downward extensions from said body simulating legs of the animal, a base portion between the lower ends of said laterally spaced leg extensions for supporting the scissors in upright position

5 on a surface and defining with the legs an apertured finger-receiving handle, said inner member having an upward extension substantially overlying said neck extension coextensively therewith and constituting the other cutting edge of the scissors, said inner member having an elongated downward extension simulating another leg of the animal and having thereon a looped portion providing an apertured finger-receiving handle in cooperation with said first-named handle, said handles being adapted to have fingers of a hand received through the apertures thereof for pivoting said members relatively of each other to provide shearing action between said cutting edges, the bottom edge portion of said looped handle being longitudinally aligned with the bottom of said base portion when said scissors are in closed condition.

4. Toy scissors for children comprising a pair of relatively thin hard plastic outer and inner members pivotally connected to each other, the inwardly opposite sides of said members being flat and engaging in flat face-to-face relation, the portion of said outer member at the pivotal area thereof being of substantially broad lateral area in simulation of the body of an animal, said outer member having an upward extension therefrom in the form of an elongated neck of the animal terminating in a laterally enlarged portion simulating a head thereof, one edge of said neck extension extending in an elongated edge from a point adjacent said pivot to adjacent the outer end of the neck extension and constituting one cutting edge of the toy scissors, said outer member having laterally spaced elongated downward extensions from said body simulating legs of the animal, a base portion between the lower ends of said laterally spaced leg extensions for supporting the scissors in upright position on a surface and defining with the legs an apertured finger-receiving handle, said inner member having an upward extension substantially overlying said neck extension coextensively therewith and constituting the other cutting edge of the scissors, said inner member having an elongated downward extension simulating another leg of the animal and having thereon a looped portion providing an apertured finger-receiving handle in cooperation with said first-named handle, said handles being adapted to have fingers of a hand received through the apertures thereof for pivoting said members relatively of each other to provide shearing action between said cutting edges.
